UNITED STATES PATENT OFFICE.

ALOIS W. FORSTER, OF BROOKLYN, NEW YORK.

METHOD AND APPARATUS FOR SHEATHING STRUCTURAL MEMBERS WITH CONCRETE.

Application filed December 22, 1927. Serial No. 241,778.

This invention relates to methods and apparatus for sheathing structural members with concrete.

An object of the invention is to provide an improved method and apparatus whereby a properly shaped sheath of concrete may be easily, speedily and economically formed about a structural member.

Another object is to provide an improved holding device whereby a wooden or other form may be readily secured to structural members of varying size and shape.

Another object is to provide a holding device whereby a plurality of forms disposed at an angle to each other may be readily secured to the structural member to be sheathed.

An additional object is to provide a device of the character described which is simple in construction and operation, and which may be readily manufactured and assembled.

Other objects of the invention will in part be obvious and will in part appear hereinafter.

The invention accordingly comprises the several steps and the relation and order of one or more of such steps with respect to each of the others, and the apparatus embodying features of construction, combinations of elements and arrangement of parts which are adapted to effect such steps, all as exemplified in the following detailed disclosure, and the scope of the application of which will be indicated in the claims.

For a fuller understanding of the nature and objects of the invention reference should be had to the following detailed description taken in connection with the accompanying drawings, in which:

Figure 1 is a perspective view of a holding device or clamp such as contemplated by the invention showing the same in operative position;

Fig. 2 is a view of a sheathed structural member with portions thereof cut away to illustrate the use of clamps such as shown in Fig. 1;

Fig. 3 is a perspective view of one of the grippers composing the clamp;

Fig. 4 is a plan view of a metallic blank marked to indicate the manner in which a plurality of grippers may be formed therefrom;

Fig. 5 is a sectional view illustrating the clamp equipped with means for holding a pair of forms at right angles to each other; and

Figs. 6 to 11, inclusive, illustrate in detail various uses of the exemplified clamp.

In sheathing structural members with concrete, and particularly when such sheathing operations are conducted with a "cement gun" or the like, it is often desirable to secure forms in proximity to the structural member to be sheathed, and especially in proximity to the edges thereof, in order that the surface of the concrete may be smooth and the corners thereof properly shaped. Such forms are ordinarily composed of wood or like material. In Patent No. 1,596,170, dated August 17, 1926, I have disclosed a holding-clip for concrete form comprising a pair of resilient members adapted to be slipped over the edge of a structural member such as an angle-iron and carrying at its opposite end a pointed or nail member which may be driven into the form. In the manufacture and use of these clips several difficulties have presented themselves, among which is the disadvantage that each clip, being designed for use on a structural member of a particular thickness, cannot be used on a structure of a different thickness, so that during operations a supply of clips of various sizes must always be kept on hand. The present invention contemplates the provision of a clip the parts of which can be manufactured with extreme ease, which can be assembled on the job, and which is adapted for use in sheathing structural members regardless of the size or shape thereof.

In the exemplified embodiment of the invention there are provided a pair of gripping members 12 formed with pointed ends 13 adapted to be driven into a form 14 composed of wood or similar material and provided at their opposite ends with gripping portions 15 adapted to be placed on opposite sides of the structural member 16 to be sheathed. These gripping members, as exemplified, are formed between their ends with a plurality of bores at 17, and there is inserted in one set of these bores a threaded bolt 18 having a cooperating nut 19, whereby the two grippers may be drawn into gripping engagement with a protruding portion of the structural member 16. In the present instance the narrow or pointed end of each gripper terminates in a pair of shoulders 20 whereby the distance which the same is driven into the form is limited, and the bores 17 thereon are positioned a distance from the shoulders 20 corresponding to the thicknesses of concrete usually employed beyond the pro-

truding edge of the structural member to be sheathed. Preferably, the grippers 12 are formed with complementary outer and inner ends so that a plurality of such members may 5 be cut out of a strip of metal without waste in the manner indicated in Fig. 4. In use, the pointed outer ends 13 of the grippers 12 are preferably first driven into the form 14, the grippers being spaced a distance sub- 10 stantially equal to the width of the structural member 16 to be gripped, the bolt 18 inserted through a set of the bores therein, the nut 19 placed thereon, the grippers placed about the member 16, and the nut turned down to 15 bring the grippers in gripping engagement with the structural member, after which the space surrounding the member 16 and between this member and the form 14 is filled with concrete by a cement gun or by other 20 suitable means. It is to be understood, of course, that certain of the steps in this method may be reversed and the method otherwise varied, if desired; and furthermore that a holding device such as contemplated by the invention may be employed in 25 a wide variety of methods and applications other than those exemplified.

In order to facilitate the breaking off of the outer ends of the grippers when desired, 30 for example, after the concrete has hardened and the form 14 has been removed therefrom, the grippers may, if desired, be scored, preferably along a line slightly within the shoulders 20, as shown at 21 in Fig. 3.

35 In certain instances it is desirable to support an additional form at an angle to the form into which the holding device is driven, and the invention, in one of its aspects, contemplates the provision, when desired, of 40 means which may be utilized to support such an additional form from the holding device. With this in view, the grippers 12 are preferably provided with an additional bore 22 adjacent the inner end thereof and in this 45 bore (or, in certain instances, in one of the bores 17) on one of the grippers there may be inserted a nail 23 (Figs 5 and 7) or like member adapted to have driven thereon a form 24, which, as exemplified, is positioned 50 parallel to the grippers and at a right angle to the form 14 into which the grippers 12 are driven. The outer edge of the form 24 is ordinarily secured at one edge of the form 14, the nail or nails 23 serving as a support 55 for the inner portion. If desired, the nail 23 may be scored as at 25 to facilitate the breaking off of the end thereof before or after the removal of the form 24. For example, the bent end of the nail may be 60 twisted after the concrete has set, so as to break the nail and to permit the ready removal of the form 24.

65 It will be readily apparent that a device such as contemplated by the invention may be utilized in a variety of different ways.

For example, there is shown in Fig. 6 a clamp with the bolt 18 inserted in the outer pair of bores 17, whereby the form 14 is held in close proximity to the protruding edge of an angle iron to which the clamp is attached; Figure 7 shows clamps employed to grip a plurality of reinforcing members and to support forms which provide a rectangular trough for the reception of concrete; in Fig. 8 a clamp is shown as used to grip a plurality of reinforcing members, as well as the angle iron to which the same are secured; Figure 9 shows a clamp employed to grip an entire side of an angle iron; Figure 10 shows a pair of clamps gripping the edges of a U-iron; and Figure 11 shows a pair of juxtaposed angle irons at each edge of which a form is secured by means of a clamp such as exemplified.

Since certain changes in carrying out the above process and in the constructions set forth, which embody the invention may be made without departing from its scope, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. The method of sheathing a structural member with concrete which comprises driving into a form each of a pair of gripping members adapted to cooperate in mutually gripping a structural member, placing said gripping members adjacent opposite surfaces of a structural member, drawing said mutual gripping members into permanent gripping engagement with said structural member, and filling with concrete the spaces about said structural member and between said structural member and said form.

2. Apparatus for sheathing a structural member with concrete including a form, a pair of grippers each independently secured thereto, and means to move said grippers toward each other and into gripping engagement with opposite surfaces of the structural member.

3. A clamp for securing a form upon a structural member to be sheathed with concrete, comprising a pair of grippers, each provided with a point adapted to be driven into a form and with a gripping surface, and means to move the gripping surfaces of said grippers toward each other and into gripping engagement with a structural member.

4. A clamp for securing a form upon a

structural member to be sheathed with concrete, comprising a pair of grippers, each provided with a pointed end adapted to be driven into a form and with opposed gripping surfaces and formed to permit operating means to be secured thereon at a plurality of positions, and operating means to move said grippers into gripping engagement with a structural member.

10 5. A clamp for securing a form upon a structural member to be sheathed with concrete, comprising a pair of grippers, each provided with a point adapted to be driven into a form, and with a pair of gripping surfaces, and screw means to move the gripping surfaces of said grippers into gripping engagement with a structural member.

6. A clamp for securing a form upon a structural member to be sheathed with concrete, comprising a pair of grippers each formed with a pointed end adapted to be driven into a form with a gripping surface at its opposite end and with a plurality of bores therebetween, a threaded bolt extending through one set of the bores in said grippers, and a nut cooperating with said bolt to draw said grippers into frictional engagement with a structural member.

7. A clamp for securing a form upon a structural member to be sheathed with concrete, comprising a pair of grippers adapted to be secured upon a structural member, each of said grippers being formed with a pointed end adapted to be driven into a form and being provided with a lateral score to facilitate the removal of the pointed end thereof after the formation of the concrete sheath.

8. In apparatus for sheathing a structural member with concrete, the combination of a clamp comprising gripping members adapted to be secured upon a structural member and means to secure a form in spaced relation to the structural member gripped by the gripping members, and means associated with said clamp to support a second form extending at an angle to the aforementioned form at a point spaced from a point where said forms meet one another.

9. In apparatus for sheathing a structural member with concrete, the combination of a clamp comprising a pair of grippers, each formed with a pointed end adapted to be driven into a form and with a plurality of bores, and means extending through a set of the bores in said grippers and adapted to draw said grippers together into gripping engagement with a structural member, and means extending through another of the bores in one of said grippers and adapted to secure an additional form in place thereon.

10. In apparatus for sheathing a structural member with concrete, the combination of a clamp comprising a pair of grippers, each formed with a pointed end adapted to be driven into a form and with a plurality of bores, and means extending through a set of the bores in said grippers and adapted to draw said grippers together into gripping engagement with a structural member, and a nail member extending through an inner bore and driven into a form positioned at an angle to the aforesaid form.

In testimony whereof I affix my signature.
ALOIS W. FORSTER.
